UNITED STATES PATENT OFFICE.

HEINRICH DECHAMPS, OF CHARLOTTENBURG, GERMANY, ASSIGNEE TO GENERAL ELECTRIC COMPANY, A CORPORATION OF NEW YORK.

CONDENSING-VENTILATOR FOR ENGINES.

1,116,030.

Specification of Letters Patent.

Patented Nov. 3, 1914.

Application filed November 12, 1913. Serial No. 800,536.

To all whom it may concern:

Be it known that I, HEINRICH DECHAMPS, a subject of the King of Prussia, residing at Charlottenburg, Germany, have invented 5 certain new and useful Improvements in Condensing-Ventilators for Engines, of which the following is a specification.

The present invention relates to means for ventilating the crank casings of engines, 10 particularly of the internal combustion type, and has for its object to improve their construction and operation.

For a consideration of what I believe to be novel and my invention, attention is directed to the accompanying description and claims appended thereto.

In the drawing is shown an internal combustion engine in vertical section.

The engine may be of any suitable construction and operate on any desired cycle. 20 As illustrated it is of the two-cycle type, there being two oppositely moving pistons in each cylinder.

1 indicates the base or crank casing of the 25 engine containing a chamber 2 in which the crank shaft 3 rotates. In the relatively air tight chamber 2 is a body of lubricant for lubricating the cranks, pistons, etc. The connecting rods for the upper and lower 30 pistons have been omitted in the interest of clearness. At the top of the crank case is a receiver 4 that supports one or more cylinders 5. In the cylinder are scavenging ports 6 receiving air from the chamber in 35 the receiver and ports 7 for the exhaust products of combustion. At the sides of the cylinder and formed in the receiver are openings 8 through which the upper piston connecting rods extend.

40 Mounted at some convenient place on the crank casing is a relatively large tubular member 9 commonly referred to as a "breather pipe or ventilator". As the pistons move in and out this member or pipe 45 serves to equalize differences of pressure between the inside and the outside of the crank chamber. The pipe also serves as a means to permit oil vapors to escape from the crank chamber to atmosphere. In order to 50 condense these relatively hot oil vapors a conduit 10 is provided that is supported in any suitable way; as for example, by screwing it into the wall 11 of the air carrying conduit 12. The conduit 10 extends through

the center of the breather pipe and the cool 55 air passing downward therethrough tends to condense the vapors as they rise and permit the oil particles to drop back into the crank chamber.

On top of the conduit 10 is a head 13 of 60 any suitable construction having an annular passage or chamber 14 that communicates with the passage in the conduit 10 and terminates at a point slightly below the upper end of the breather pipe 9. As shown, the 65 head comprises a pair of thin metal plates that are down turned at their outer edges and are separated from each other by space blocks 15. The edge of the under disk extends below the upper end of the breather 70 pipe so that vapor escaping from the latter must flow past the annular passage between said plates. The relation of the head and breather pipe is such that the vapors can escape from the latter without undue restriction. Further, owing to the relation of the parts, the said escaping vapors are sucked into the conduit 10 along with the supply of fresh air and flow with it through the conduit 12. In a two-cycle engine as 80 shown, the conduit 12 supplies air to the scavenging pump which in turn delivers it to the chamber in the receiver 4 and from there to the working cylinder. The pump is not shown as it seems unnecessary to an 85 understanding of my invention. In the case of a four-cycle engine the air from the conduit 12 may pass directly to the cylinders, subject, of course, to the usual valve control. In the event that it is undesirable for any 90 reason to entrain the uncondensed gases from the crank chamber with the fresh air supplied to conduit 12, the shape of the head may be so modified as to prevent the gases and air from mixing. In other words, the 95 two features of my invention: *i. e.*, condensing of the oil vapors, and supplying uncondensed gases to the working cylinder can be used together or separately. By unscrewing the tube 10 the breather pipe can be 100 easily removed. The conduit 12 may be formed separately instead of forming a part of the base casting.

In accordance with the provisions of the patent statutes, I have described the principle of operation of my invention, together with the apparatus which I now consider to represent the best embodiment thereof; but

I desire to have it understood that the apparatus shown is only illustrative, and that the invention can be carried out by other means.

What I claim as new and desire to secure by Letters Patent of the United States, is,—

1. In an engine of the character described, the combination of a chambered crank casing adapted to contain lubricant, a working cylinder, a breather pipe opening into the casing through which vapors can pass to the atmosphere, and a conduit for supplying fresh air to a working cylinder that is so positioned with respect to the breather pipe as to condense vapors passing therethrough.
2. In an engine of the character described, the combination of a chambered crank casing adapted to contain lubricant, a working cylinder, a breather pipe that extends into the casing and is open at both ends to permit the escape of gases, and a conduit for supplying fresh air to a working cylinder that is so positioned with respect to the breather pipe as to condense vapors passing therethrough, one end of said conduit terminating at approximately the end of said pipe so that uncondensed vapors will be entrained with the fresh air entering the conduit.
3. In an engine of the character described,

the combination of a chambered crank casing adapted to contain lubricant, a working cylinder, an open ended breather pipe that extends into the casing and through which oily vapors escape, and a conduit for supplying cool fresh air to a working cylinder which extends longitudinally through the pipe for the purpose of condensing the vapors passing out through said pipe.

4. In an engine of the character described, the combination of a chambered crank casing adapted to contain lubricant, a working cylinder, an open ended breather pipe that extends into the casing and through which oily vapors escape, a conduit for supplying cool fresh air to a working cylinder which extends longitudinally through the pipe for condensing the vapors passing out through said pipe, and a head for the conduit that projects over the pipe so that vapors escaping from the latter will flow with fresh air through the head into the conduit.

In witness whereof, I have hereunto set my hand this 25th day of October, 1913.

HEINRICH DECHAMPS.
